BALANCED WRENCH

THERON W. REYNOLDS, WELLSVILLE, N. Y.

Application July 24, 1950, Serial No. 175,593

4 Claims. (Cl. 81—121)

1
The present invention relates to improvements in a wrench and has for an object the provision of a device of this kind which affords to the user a greater amount of flexibility and latitude than is possible with similar wrenches of the prior art.

Another object of the present invention is to provide an improved wrench comprising a shank, a counterbalance portion being provided on each end of said shank, one of said portions extending to one side of said shank, the other of said portions extending to the opposite side of the shank with reference to said one portion to provide a balanced wrench, and at least one of said portions having an aperture therein for receiving the head of a pipe plug or the like, at least said apertured portion being oval shaped to provide major and minor axes, said aperture being substantially square shaped and having one pair of opposed walls disposed at substantially right angles to the major axis of the oval of the apertured portion and the other pair of opposed walls disposed substantially parallel to the major axis of the oval of the apertured portion, said aperture lying between the outer end of said apertured portion and its minor axis.

A further object of the present invention is to provide an improved wrench comprising a shank having substantially straight sides throughout its entire length, a counterbalance portion on each end of said shank, the major part of one of said portions extending to one side of the longitudinal axis of the shank, the major part of the other of said portions extending to the opposite side of the longitudinal axis of the shank to provide a balanced wrench, and at least one of said portions having an aperture therein for receiving the head of a pipe plug or the like, said opening being disposed entirely beyond a prolongation of that side of the shank towards which the major part of the apertured portion extends.

A still further object of the present invention is to provide an improved wrench which is perfectly balanced so that it can be used for long periods of time without undue fatigue to the user thereof.

In one of its broadest aspects the present invention contemplates the provision of a wrench comprising a shank substantially straight throughout its entire length, a head mounted on one end of said shank and extending to one side thereof at an angle of the order of 22½ degrees, and a second head mounted on the opposite end of said shank and extending to the opposite side thereof at an angle of the order of 22½ degrees, each of said heads having a square shaped opening therein.

2
With the foregoing and other objects in view, the invention will be hereinafter more fully described and more particularly pointed out in the appended claims.

5 In the drawings, in which the same parts are denoted by the same reference numerals throughout the several views;

10 Figure 1 is a plan view of the improved wrench constructed in accordance with the present invention;

Figure 2 is a side elevational view of the improved wrench with parts broken away and in section;

15 Figure 3 is a sectional view taken on the line 3—3 of Figure 1 and looking in the direction of the arrows; and

20 Figure 4 is a plan view of a square divided into sixteen 22½ degree angles and showing in phantom lines the eight positions assumed by the wrench in making the eight point openings.

25 Referring more particularly to the drawings, 16 indicates the shank or handle of the wrench which may be made of steel or any other suitable material. The handle may be of any desired length and shape, but in the present illustration it is shown to be round in cross section, as can be seen from Figure 3 of the drawing.

The opposite ends of the shank 16 are tapered downwardly and outwardly as indicated at 11 and 12. The tapered portion 11 merges into a relatively flat head 13. The head 13 is substantially oval shaped and the major axis 14 thereof is disposed at an angle to the longitudinal axis of the shank 16, for example at an angle of the order of 22½ degrees so that a portion of the head 13 is disposed to one side of the shank 16. The head 13 is provided with a substantially square shaped opening 15 entirely disposed within the portion of the head which extends to one side of the shank 16 and which is located adjacent to its outer free end. The outer free end of the head 13 is curved or rounded, as indicated at 13a and 13b. The center of the square opening

40 15 coincides with the center of the curve 16 on the extreme end of the head 13 on an angle of the order of 22½ degrees or on whatever angle the major axis 14 of the head 13 is disposed with respect to the longitudinal axis of the shank 16. 45 The opposite walls 17 of the opening 15 are substantially parallel with the major axis 14 of the head so that the walls 17 are disposed at the same angle to the longitudinal axis of the shank 13 as the major axis 14 is disposed to the longitudinal axis of the shank, which in the pres-

ent illustration is $22\frac{1}{2}$ degrees. The opposite walls 18 of the opening 15 are disposed at substantially right angles to the major axis 14 of the head 13.

The tapered portion 12 of the shank 10 merges into a relatively flat head 19 which is of substantially the same oval shape as the head 13. The major axis 20 of the head 19 is disposed at substantially the same angle to the longitudinal axis of the shank 10 which in the drawings is illustrated to be an angle of the order of $22\frac{1}{2}$ degrees so that a portion of the head 19 extends laterally from the shank 10. As is shown more closely in Figure 3 of the drawings, the head 19 extends from the shank 10 to the opposite side thereof to that to which the head 13 extends and to substantially the same amount in order to provide a well balanced wrench and to make possible the eight point opening mentioned above.

The head 19 has a substantially square shaped opening 21 therein which is located adjacent to its outer free end and entirely disposed within the portion of the head which extends to the side of the shank 10. The outer free end of the head 19 is curved or rounded, as indicated at 22 and the sides of the head are curved as at 19a and 19b. The center of the square opening 21 coincides with the center of the curve 22 on the extreme end of the head 19 on an angle of the order of $22\frac{1}{2}$ degrees or on whatever angle the major axis 20 of the head 19 is disposed with respect to the longitudinal axis of the shank 10. The opposite walls 23 of the opening 21 are substantially parallel with the major axis 20 of the head 19 so that the walls 23 are disposed at the same angle to the longitudinal axis of the shank 10 as the major axis 20 is disposed to the longitudinal axis of the shank which, in the present illustration, is $22\frac{1}{2}$ degrees. The opposite walls 24 of the opening 21 are disposed at substantially right angles to the major axis 20 of the head 19.

In the drawings, the opening 15 is illustrated as being larger than the opening 19 so that the wrench will fit different size pipe plugs, it is to be understood that the openings may be of the same size or of any desired different relative sizes. The wrench itself can be made in assorted sizes so that a particular wrench may fit two different size plugs, one for each end and that the wrenches themselves can be made in assorted sizes so as to cover a wide range of openings.

In the use of the device, the opening in either head will be fitted over the head 25 of a pipe plug for example. If the pipe plug is situated in close quarters, the user of the improved wrench has available to him eight possible positions of the wrench in which the opening 15 or 21 can be fitted over the head of the pipe plug. These eight positions are clearly shown at *a* through *h* in phantom lines in Figure 4 of the drawings. For example, if the wrench cannot be applied to the head 25 of the pipe plug in the position indicated at *a* on account of some adjacent obstruction interfering with the shank 10 of the wrench, the user will rotate the head 13 of the wrench through 180 degrees around the longitudinal axis of the shank 10. The shank 10 will then assume the position indicated at *b* so that the shank will be clear of the obstruction and the wrench can be manipulated to turn the pipe plug.

Figure 4 more clearly illustrates what is meant by the eight point opening described above. In this Figure 4, A generally indicates a circle of 360 degrees divided into sixteen sectors 26 each

of $22\frac{1}{2}$ degrees. Starting from any sector 26 on the circle A with the wrench, place the opening 15 or 21 on the head 25 of the pipe plug as at position *a*, then reverse the head of the wrench to the position *b*. This would move the head 25 substantially 45 degrees. If the same procedure is followed around the circle A it can readily be seen this gives an eight point opening. Such a structure imparts a ratchet effect to the improved square wrench.

The square openings 15 and 21 fit the square head 25 of the pipe plug and the grip of the wrench is positive so that there will not be any breaking out at any of the four corners of the opening 15 or 21. The curves 16 and 22 on the extreme ends of the heads 13 and 19 and the curved sides 13a, 13b and 19a, 19b of the heads 13 and 19, respectively, permit rotation of the wrench without encountering obstructions. These curved portions of the heads and the thinness of the heads permits the wrench to reach the most difficult places to easily remove or replace various square headed objects. The oppositely disposed arrangement of the heads 13 and 19 imparts to the wrench a perfect balance so that it can be used for long periods of time without undue fatigue to the operator. The angular arrangement of each head with respect to the shank 10 will also provide a comfortable grip at each end of the wrench when the opposite head is engaging the object to be rotated. The improved wrench can also be used in tapping and retapping bolt holes and on pipe taps in various sizes and also for reaming in difficult places, as well as for other conventional uses of a wrench.

It is obvious that various changes and modifications may be made in the details of construction and design of the above specifically described embodiment of this invention without departing from the spirit thereof, such changes and modifications being restricted only by the scope of the following claims.

What I claim is:

1. An improved wrench comprising a shank, a counterbalance portion being provided on each end of said shank, one of said portions extending to one side of said shank, the other of said portions extending to the opposite side of the shank with reference to said one portion to provide a balanced wrench, and at least one of said portions having an aperture therein for receiving the head of a pipe plug or the like, at least said apertured portion being oval shaped to provide major and minor axes, said aperture being substantially square shaped and having one pair of opposed walls disposed at substantially right angles to the major axis of the oval of the apertured portion and the other pair of opposed walls disposed substantially parallel to the major axis of the oval of the apertured portion, said aperture lying between the outer end of said apertured portion and its minor axis.

2. An improved wrench comprising a shank having substantially straight sides throughout its entire length, a counterbalance portion on each end of said shank, the major part of one of said portions extending to one side of the longitudinal axis of the shank, the major part of the other of said portions extending to the opposite side of the longitudinal axis of the shank to provide a balanced wrench, and at least one of said portions having an aperture therein for receiving the head of a pipe plug or the like, said aperture being disposed entirely beyond a prolongation of that

side of the shank towards which the major part of the apertured portion extends.

3. An improved wrench comprising a shank having substantially straight sides throughout its entire length, a counterbalance portion on each end of said shank, the major part of one of said portions extending to one side of the longitudinal axis of the shank, the major part of the other of said portions extending to the opposite side of the longitudinal axis of the shank to provide a balanced wrench, and at least one of said portions having an aperture therein for receiving the head of a pipe plug or the like, said aperture being disposed entirely beyond a prolongation of that side of the shank towards which the major part of the apertured portion extends, the outer free end of said apertured portion being curved, and the center of the aperture coinciding with the center of curvature of the outer free end of the apertured portion.

4. An improved wrench comprising a shank substantially straight throughout its entire length, a counterbalance portion being provided on each end of said shank, one of said portions extending to one side of said shank at an angle of the order of twenty-two and one-half degrees to the longitudinal axis of the shank, the other of said portions extending to the opposite side of the shank with reference to said one portion and at an angle of the order of twenty-two and one-half degrees to the longitudinal axis of the shank to provide a balanced wrench, and at least one of said portions having an aperture therein for re-

ceiving the head of a pipe plug or the like, said shank being substantially round in cross section, at least said apertured portion being oval shaped to provide major and minor axes, and being integral with said shank and reduced in thickness and flat, said aperture being substantially square shaped and having one pair of opposed walls disposed at substantially right angles to the major axis of the oval of the apertured portion and having the other pair of opposed walls disposed substantially parallel to said major axis.
